UNITED STATES PATENT OFFICE

156,783

COMBINED CLOCK, CLOCK CONTROL, CONDIMENTS HOLDERS, AND SHELF FOR COOKING STOVES

Jack B. Stuman, Rockford, Ill., assignor to Geo. D. Roper Corporation, Rockford, Ill., a corporation of Illinois

Application November 8, 1946, Serial No. 134,603

Term of patent 3½ years

(Cl. D81—25)

To all whom it may concern:

Be it known that I, Jack B. Stuman, a citizen of the United States, residing at Rockford, in the county of Winnebago and State of Illinois, have invented a new, original, and ornamental Design for a Combined Clock, Clock Control, Condiment Holders, and Shelf for Cooking Stove, of which the following is a specification, reference being had to the accompanying drawing, forming part thereof.

In the drawing:

Figure 1 is a top plan view of a combined clock, clock control, condiment holders, and shelf for cooking stove embodying my new design;

Figure 2 is a front view in elevation thereof; and

Figures 3 and 4 are end elevations looking at the left and right hand ends, respectively, of Figure 2.

The dominant feature of the design resides in the portions shown in full lines.

I claim:

The ornamental design for a combined clock, clock control, condiment holders, and shelf for cooking stoves, substantially as shown and described.

JACK B. STUMAN.
